UNITED STATES PATENT OFFICE

2,356,235

AIR COOLER AND PURIFIER

James N. Fulcher, Vernon, Tex.

Application April 23, 1943, Serial No. 484,267

1 Claim. (Cl. 261—11)

This invention appertains to new and useful improvements in air conditioning apparatus and more particularly to an apparatus for cooling and purifying air.

An important object of the present invention is to provide an apparatus wherein air can be cooled in high temperature weather, quickly, efficiently and at a very low cost.

Another important object of the invention is to provide an air conditioning apparatus of the character stated which is of simple construction and of low cost to manufacture, the same having its parts so arranged as to be readily accessible for the purpose of repairs or replacements.

Other objects and advantages of the invention will become apparent to the reader of the following description.

In the drawings:

Figure 1 is a side elevational view of the apparatus.

Figure 2 is front elevational view of the apparatus.

Figure 3 is a section on the line 3—3 of Figure 2.

Figure 4 is a horizontal sectional view on the line 4—4 of Figure 1.

Figure 5 is a fragmentary vertical sectional view on the line 5—5 of Figure 1.

Figure 6 is a fragmentary elevational view 30 showing the spider for the drum.

Figure 7 is a longitudinal sectional view through the drum.

Referring to the drawings wherein like numerals designate like parts, it can be seen that the numeral 5 denotes a cabinet having a hinged top 6 and below this top is a horizontal partition 7 for supporting ice 8 or other cooling media. The partition 7 has openings 9 therein through which cold water from the ice 8 can drip onto a cylinder unit generally referred to by numeral 10 and which operates in a pan 11 containing a certain amount of lime which mixes with water 12, which may be an initial amount of water placed there or that from drippings from the ice 8. A valved drain 13 is provided for the pan 11.

The cabinet 5 has a vertical partition 14 therein extending from the bottom 15 to the partition 7 and this has a circular opening therein for receiving one end of an elongated cylinder 16 which is the inner cylinder of the drum 10. Numeral 17 denotes an outer cylinder for the drum unit 10 and both of these cylinders have perforations 18. A plate 19 closes one end of the drum unit 10 while a ring 20 closes the remaining end of the short outer cylinder 17, thus defining a chamber in which loose shavings, excelsior or like material denoted by numeral 21 is placed to hold moisture.

A packing collar 22 is provided on the parti-

tion 14 where the elongated cylinder 16 passes through the partition 14. At this end of the drum unit 10, the cylinder 16 has a spider 23 therein through which a shaft 24 is disposed.

5 this shaft extending through the other end of the drum and being supported by a bearing 25.

The forward end of the shaft 24 has a gear 26 meshing with a gear 27 on a lower countershaft 28 which is equipped with a pinion 29 meshing with a pinion 30 on a vertical shaft 31 which is geared to the armature shaft of an electric motor 32 held by brackets 33 in back of an opening 34 in the front wall of the cabinet 5. This opening 34 has grill bars 35 therein and behind 15 the bars 35 is a fan 36 carried by the armature shaft of the motor 32.

One side wall of the cabinet 5 has an opening 37 therein and in this opening is an open grill 38.

20 It can now be seen, that with the motor 32 operating, the drum unit 10 is slowly turned as it dips in the lime content of the pan 11. Air is sucked through the drum unit 10 and through the opening 37 and in passing through the drum unit 10 it is cooled by contact with the cold lime water and the lime in the water serves to convert carbon dioxide into calcium carbonate. The fan 36 draws this cool air from the elongated cylinder 16 and forces the same through the opening 34 in the front wall of the cabinet.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

In air conditioning apparatus, a cabinet having a horizontal upper partition therein forming with the upper portion of the cabinet an ice containing compartment, a vertical transverse partition in said cabinet below the horizontal partition dividing the cabinet below said ice containing compartment into an air intake and a discharge compartments, respectively, the horizontal partition being perforated above the air intake compartment to permit drippings from the ice in said ice containing compartment to escape into the air intake compartment, an air inlet and an air outlet in said cabinet opening into the air intake and out of the air discharge compartment, respectively, a liquid containing pan in the air intake compartment, a perforated drum unit journaled at one end in said transverse partition for rotation in said pan and to open into said air discharge compartment, a motor fan unit in said air discharge compartment opposite said outlet, and gearing between 50 the motor of said unit and said drum.

JAMES N. FULCHER.
